MANICURING DEVICE

John Albert Chappuis, Neuchatel, Switzerland

Application June 24, 1950, Serial No. 170,067
In Switzerland July 4, 1949

13 Claims. (Cl. 30—26)

1

This invention relates to a new or improved manicuring device for trimming nails.

The primary object of the invention is the provision of a manicuring device of particularly simple and neat construction.

A further object of the invention is the provision of a manicuring device embodying a nail-cutting element formed as a metal strip.

A further object of the invention is the provision of a manicuring device embodying a nail-cutting element in the form of a metal strip having nail-cutting edges of a particularly effective form.

A further object of the invention is the provision of a manicuring device for trimming nails which is particularly well adapted to be manufactured by mass production methods so that the device can be made in a particularly inexpensive manner.

Other objects of the invention will become apparent from the following description and claims, and from the following drawings, in which:

Figure 1 is a side elevation of one form of manicuring device embodying the present invention and showing the mode of operation of the device.

Figure 2 is a perspective view of the device shown in Figure 1 with the various parts thereof detached from one another.

Figure 3 is a cross sectional view to an enlarged scale on the line 3—3 of Figure 1.

Figure 4 is a longitudinal sectional view of part of the nail-cutting element of the device depicted in Figure 1.

Figure 5 is a view similar to Figure 4 showing one of the stages in the manufacture of the element.

Figure 6 is a plan view of part of the completed element shown in Figure 4, the view being taken looking at the underside of that figure and being on a scale less than that of Figure 4.

Figures 7, 8 and 9 are views similar to Figure 6 showing three modifications.

Referring firstly to Figures 1 to 3 of the drawings, the manicuring device there illustrated comprises a body 10 of relatively flat and largely circular configuration, the body consisting of two identical body parts 11, 12, each conveniently formed by moulding the same in a suitable plastic, the two parts forming each body being moulded in a material of the same colour but preferably of dissimilar colours, for example, one a white colour, and the other a red, green or other contrasting colour, so that the assembled

article presents a novel and striking appearance.

Each body part is of substantially disc-like configuration comprising a flat inner face 13 of annular configuration, the peripheral edge of each face being largely of part-circular configuration as indicated at 14, each such peripheral edge being formed adjacent the face 13 and medially of the circumferential length of such edge with a recess 15, the base of which recess is formed with an arcuate groove 16 disposed a short distance inwardly of the peripheral edge 14, each groove being adapted when the parts are assembled, to receive one of the two longitudinal edges 17 of the elongated part-circular strip metal nail-cutting element which is shown at 18.

Each body part 11, 12 is formed adjacent the recess 16 with a number of circular holes 19 spaced apart equidistantly and symmetrically along the length of the recess, the edge of each of such holes which is more remote from the centre of the body part merging into the recess 15 so that this is interrupted at positions corresponding to each hole 19, while each hole 19 extends inwardly of the body part beyond the inner wall 20 of the groove 16.

These holes 19 serve to permit of egress of the nail parings during the operation of the device.

Each body part 11, 12 is formed centrally on its flat face 13 with a circular recess 21 so that when the two parts are assembled, the two recesses 21 collectively provide a housing as shown in Figure 3, in which a spare cutting element indicated at 22 in that figure may be disposed with the element bent to a curvature greater than its natural curvature shown in Figure 2, so as to engage resiliently with the circular wall of the recesses 21 and thereby to be retained in position.

For securing the two body parts together, the annular flat face 13 thereof is provided in each case with an upstanding connecting pin 23 of slightly tapered configuration, each pin being adapted frictionally to engage within a correspondingly tapered recess 24 when the two body parts are brought together with the flat faces 13 thereof face to face with one another.

To facilitate operation of the device, each body part is formed on its periphery at a position diametrically opposite to the recess 16 with a handle portion 25, the two handle portions being thus brought into overlapping relationship with one another when the two parts are assembled together, and the opposed faces of these handle

portions are formed near the outer edge thereof with recesses 26 so that by the insertion of the thumb nail of the user therebetween, the two body parts can be forced apart to permit when necessary of the removal and replacement of the cutting element, the parts being secured together by squeezing them between the thumb and finger of the user so that the pins 23 engage frictionally with their corresponding recesses 24, thus effectively securing the parts together against relative movement when the device is either in or out of use.

Each body part is recessed peripherally at 27, 28 on each side of each handle portion 25, and each recess 28 which is adjacent the pin 23 is provided centrally with a nail-cleaning part 29 adapted to be inserted at the back of the user's nail in the known manner. As will be apparent from Figure 1, when the two parts 11, 12 are assembled, the two nail-cleaning parts 29 are spaced apart from one another so that either part may be used as desired.

As will be clear from the above description and from an examination of Figure 2, the two body parts 11, 12 are completely identical with one another, that is to say, either part may be formed from the same moulding dies with resultant saving in production costs.

Each body part preferably has its outer face formed as a central cylindrical portion 30 surrounded by an outwardly tapered annular face 31 as shown in Figure 3, the cylindrical portion 30 being formed peripherally with an upstanding circular rim 32 which bounds a central flat face 33 which may serve to carry advertising and similar matter.

The nail-cutting element 18 is of a length corresponding exactly to the length of the groove 16 so that the ends 34 of the element abut against the ends 35 of the groove 16 and recess 15, while the width of the element corresponds to the distance between the bases of the two grooves 16 when the two body parts are assembled together, so that the element is located against all movement in relation to the body 10 during the nail-cutting operation.

The cutting element 18 is formed from a long length of relatively high carbon steel strip of width and thickness similar to that shown in Figure 2, and a long length of the strip is advanced past a punch to form therein a succession of equally spaced depressions 36 so that the strip in longitudinal cross section is as shown in Figure 5, each such depression being of frusto-conical form internally and being formed by a male punch operating on the upper side of the strip in Figure 5 and co-operating with a female die adapted to form the strip successively to the sectional shape illustrated so that the strip is formed on its under side in Figure 5 at a position centrally of each recess 36 with a dependent cylindrical portion 37 with the thickness of the metal in the peripheral part of each recess 36 decreasing towards the cylindrical portion 37, that is to say, the part of the strip indicated at 38 in Figure 5 is of tapered form in cross section.

The long length of metal strip is now cut into lengths corresponding to the length of the nail-cutting element, each cut length of strip is then heat-treated so as to harden and temper it in the known manner, and finally the cylindrical portions 37 are ground away so as to form adjacent the smaller diameter of each recess 36 flat annular faces 39 disposed with their planes parallel to the plane of the strip, the inner edges 40

of which are relatively sharp and constitute cutting edges extending peripherally around the now-formed holes 41 in the strips.

The strip is now bent to the curved configuration indicated in Figure 2 corresponding to the curvature of the groove 16 and presents to the outer peripheral opening 42 of the recess 15 a series of cutting edges spaced along the length of the groove, which cutting edges adjacent the longitudinal centre line of the cutting element 18, i. e. at the faces indicated at 43 in Figure 6, are adapted to trim the user's nail, trimming being effected by positioning the user's finger in relation to the device as shown in Figure 1 with the flesh of the finger adjacent the nail engaging with the adjacent periphery 44 of the body part of one side of the opening 42, so that the edge of the nail projects into the opening 42 for engagement with the cutting edge parts 43, and as the nail is drawn along the length of the cutting element 18, the desired trimming is effected, the nail parings falling out through the holes 19.

The trimming operation can be effected in several different ways, for example, by drawing the nail continuously across the cutting edge of one of the holes 41 in the cutting element, by drawing the nail along the whole length of the cutting element, or by turning the body so that the cutting element has in effect a rolling engagement with the edge of the nail.

In Figures 7, 8 and 9 are depicted alternative shapes to the holes 41 in the cutting element. These are formed in a manner similar to the construction already described.

The manicuring device particularly described above is extremely convenient to handle, can readily be disposed in the pocket or handbag of the user, it presents a neat appearance and can readily and inexpensively be made by mass production methods, while when a cutting element has become worn, it can readily be replaced.

What I claim then is:

1. A manicuring device comprising a body, a strip metal nail-trimming element formed separately from the body, means on said body engaging detachably peripheral portions of said nail-trimming element, means on said body retaining said element releasably against movement relative to said body, and said element having nail-trimming parts adapted to engage and trim a nail of the user when the body is displaced relative to the nail in close proximity therewith.

2. A manicuring device comprising a body, an elongated strip metal nail-trimming element formed separately from the body, said body having a peripheral opening, said body having recesses on opposite sides of said opening receiving detachably opposite longitudinal edges of said nail-trimming element, means on said body retaining said element releasably against movement relative to said body, and said element having nail-trimming parts adapted to engage and trim a nail of the user when the body is displaced relative to the nail in close proximity therewith.

3. A manicuring device comprising a body of flat form having a convex peripheral edge, an elongated strip metal nail-trimming element formed separately from the body, said body having a peripheral opening in said peripheral edge thereof, said body having grooves on opposite sides of said opening receiving detachably opposite longitudinal edges of said nail-trimming element, means on said body retaining said element releasably against movement relative to said

body, and said element having nail-trimming parts adapted to engage and trim a nail of the user when the body is displaced relative to the nail in close proximity therewith.

4. A manicuring device comprising a body, said body consisting of two identical parts of substantially flat form, means connecting said two body parts detachably together in opposed face to face relationship, each of said body parts being formed in their opposed faces with a groove of part-circular form, an elongated arcuate shaped strip metal nail-trimming element having its two longitudinal edges located one in each groove with its ends in engagement with the ends of each of said grooves, each of said body parts adjacent the said groove therein being formed with a peripheral opening, said element extending transversely of said opening and spaced inwardly thereof by a distance sufficiently small as to permit of engagement of the user's nail with the trimming element to effect trimming thereof when the body is displaced relative to the nail of the user in a direction along the length of the element.

5. A nail manicuring device comprising a body consisting of a pair of identical body parts connected detachably together in face to face overlapping relationship, said body parts being formed with a recess along each of their opposed faces adjacent the periphery of the body, said recesses being disposed opposite to one another and extending each for a portion of the peripheral length of said body and co-operating with one another to provide a peripheral opening in said body, each of said body parts having a groove in the recess therein, said two grooves being disposed opposite to one another and extending longitudinally of the corresponding recess, an elongated strip metal cutting element provided with nail-cutting edges extending transversely to said peripheral opening with its longitudinal edges disposed in one of each of said grooves, said element being disposed immediately inwardly of said peripheral body opening to receive the end of the user's nail, while the cutting edges of said element are shielded by the peripheral edges of said opening and opposite ends of said strip metal cutting element abut opposite ends of said body grooves.

6. A nail manicuring device comprising a body having a peripheral opening extending for a portion of the peripheral length of said body, said body having a pair of opposed grooves disposed on opposite sides of said opening and spaced inwardly from the mouth of said opening at the periphery of said body, an elongated strip metal nail-cutting element extending transversely to said peripheral body opening with its longitudinal edges disposed one in each of said grooves, said element being disposed immediately inwardly of the mouth of said peripheral body opening to receive the end of the user's nail, while the cutting edges of said element are shielded by the peripheral edges of said opening and opposite ends of said strip metal cutting element abut opposite ends of said body grooves.

7. A manicuring device comprising a body, said body consisting of two parts, means connecting said two body parts detachably together in opposed face to face relationship, each of said body parts being formed in their opposed faces with a groove of part-circular form, an elongated strip metal nail-trimming element having its two longitudinal edges located one in each groove with its ends in engagement with the ends of each of said grooves, each of said body parts adjacent the said groove therein being formed with a peripheral opening, said element extending transversely of said opening and spaced inwardly thereof by a distance sufficiently small as to permit of engagement of the user's nail with the trimming element to effect trimming thereof when the body is displaced relative to the nail of the user in a direction along the length of the element.

8. A device according to claim 7, wherein each body part is provided with a pin of tapering frusto-conical configuration adapted to engage frictionally in a correspondingly shaped opening formed in the other body part to secure the two body parts frictionally but detachably together.

9. A device according to claim 5, wherein each body part is formed adjacent the groove therein with a plurality of spaced openings extending between the groove and the outer face of said body part remote from the other body part, for the purpose specified.

10. A device according to claim 4, wherein the opposed faces of each body part are formed centrally of such face each with a recess, the two recesses collectively accommodating a spare nail-trimming element.

11. A device according to claim 1, wherein the strip metal nail-trimming element is formed with a number of holes therein spaced apart along the length of said element, the edges of said holes constituting nail-cutting edges.

12. A device according to claim 1, wherein the strip metal nail-trimming element is formed with a number of holes therein spaced apart along the length of said element, the edges of said holes constituting nail-cutting edges, each of said holes being of circular configuration.

13. A device according to claim 1, wherein the strip metal nail-trimming element has a series of holes therein spaced apart along the length of the strip, the edges of said holes being pressed out of the plane of the strip at one side thereof and forming nail-cutting edges with the outer face of the pressed part of plane annular form and extending parallel to the plane of the strip to form one side of the nail-cutting edge, the opposite side of which is formed by the interior of the hole, which interior tapers axially of the hole towards the plane side of the cutting edge.

JOHN ALBERT CHAPPUIS.
